CLAIM

The ornamental design for "shoe orthotic," as shown and described.

DESCRIPTION

FIG. 1 is a top perspective view of a shoe orthotic.

FIG. 2 is a bottom, front perspective view of the shoe orthotic of FIG. 1.

FIG. 3 is a bottom, rear perspective view of the shoe orthotic of FIG. 1.

FIG. 4 is a top view of the shoe orthotic of FIG. 1.

FIG. 5 is a bottom view of the shoe orthotic of FIG. 1.

FIG. 6 is a front view of the shoe orthotic of FIG. 1.

FIG. 7 is a rear view of the shoe orthotic of FIG. 1.

FIG. 8 is a right side view of the shoe orthotic of FIG. 1; and, FIG. 9 is a left side view of the shoe orthotic of FIG. 1.

The shoe orthotics of FIGS. 1-9 is for a left foot. A complementary shoe orthotic for a right foot is the mirror image of the shoe orthotic for the left foot.

The lighter solid lines denote surfaces and contours. Line shading is not surface ornamentation.

1 Claim, 9 Drawing Sheets
